UNITED STATES PATENT OFFICE.

JOHN RICHARD EDWARDS, OF VANCOUVER, BRITISH COLUMBIA, CANADA, ASSIGNOR
TO AMERICAN CAN COMPANY, OF NEW YORK, N. Y., A CORPORATION OF NEW
JERSEY.

CAN-COVER-COUNTING MACHINE.

Application filed May 1, 1924. Serial No. 710,286.

The present invention relates to a machine for counting can ends and arranging them in groups of desired magnitude conveniently located for removal and packing for shipment.

In accordance with modern canning practice, the can covers are supplied to the packers separately from the can bodies and can most conveniently be packed and shipped in boxes entirely independently of the method of shipment of the can bodies. It is, therefore, highly important that these covers be supplied in proper quantity so that the customer will have a sufficient number to close all of the cans which he receives and still not have an excess, resulting in wastage. Inasmuch as the ends are manufactured at a high rate of speed by automatic machinery, it is desirable that they be accurately counted and arranged for packing without retarding the production in the factory. The purpose of the present invention is, therefore, to provide a machine for rapidly and correctly counting the covers and arranging them in proper groups for packing, with a minimum requirement for the services of attendants and by means of automatically controlled mechanism of simple and efficient operation.

An important feature of novelty in the present invention is the positive actuation of the cover counting mechanism by contact of the covers as they are individually propelled through the separating and feeding devices of the machine.

Another feature of the invention is the provision of means for automatically terminating the action of said separating and feeding devices when the supply of covers runs low in the chute through which they are delivered, thus insuring that the supply will be replenished at the proper time and preventing inaccurate results due to the continued operation of said devices when no covers are in position to be acted upon thereby.

Numerous other objects and advantages of the invention will be apparent as it is better understood from the following description, which, taken in connection with the accompanying drawings, discloses a preferred embodiment thereof.

Referring to the drawings,

Figure 1 is a side elevation of a machine in which my invention is embodied, show-

ing the stacked covers in position for counting;

Fig. 2 is an enlarged central sectional view, taken substantially along section line 2-2 of Fig. 3 and being partly broken away to better illustrate certain of the operating parts;

Fig. 3 is an elevational view, taken from the plane designated by the line 3-3 in Fig. 2; and

Fig. 4 is a cross-sectional view of the stack holder and separating device, being taken substantially along the line 4-4 of Fig. 2.

The covers to be counted are positioned in stacked formation in a chute 11 formed integrally with a transverse web 12 connecting side frames 13 and 14, which rest upon supporting legs 15. A trough 16 is supported from forward extensions of the side frames 13 by means of yokes 17 and 18 and is adapted to receive the ends after they are counted and arranged in groups of predetermined size for packing.

The covers from a stack 19 in the chute 11 are adapted to be separated and propelled individually by and between cylindrical drums 21, mounted for rotation at the base of said chute and provided with spiral grooves 22, which are cut in the peripheral faces thereof. For the purpose of rotating said drums, a drive shaft 23, receiving power through a pulley 24, is provided with spiral gears 25 and 26 disposed within and adjacent bearings 27 and 28 and meshing with intermediate spiral gears 29 and 31, which are carried upon studs 32 and 33 and in turn mesh with other spiral gears 34 and 35 secured to the upper ends of shafts 36 and 37, which have bearings in the frame and carry the feeding drums 21.

By the mechanism just described, said drums 21 are rotated in timed relation, the open upper ends of the grooves 22 being positioned at the opposite sides of each can cover as it is separated from the stack by means shown particularly in Figs. 3 and 4. The stack of ends is normally supported upon inwardly extending fingers 38 formed upon oppositely disposed levers 39 pivoted respectively at 41 and 42 in the frame. Said levers are adapted to be actuated to move the fingers 38 in and out in timed relation with the rotation of the drums 21 by means of cams 43 carried upon

the shafts 36 and 37 just above said drums 21. The levers 39 are held against said cams by means of springs 44 secured at one end to said levers and at the opposite end to hooks 45 fixedly secured in the frame. Upon withdrawal of the fingers 38, the lowermost end of the stack comes in contact with the tops of the drums 21 and in position to enter the open upper ends 19 of the grooves 22, as they are presented. Continued rotation of the shafts 36 and 37 causes the fingers 38 to enter between said lowermost end and the one next above it to support the remainder of the stack and the separated cover is propelled downwardly within and by the grooves of said drums 21. It will be noted that said drums are flared outwardly toward their lower ends, this being for the purpose of narrowing 20 the space between the walls of opposite grooves, causing the covers to be crowded forward and partially removed from between said drums and turned toward the vertical position in which they are arranged in the trough or chute 16. The covers are thus transferred positively from the delivery chute 11 to the receiving chute 16 one after another in separated relationship, as shown in Fig. 2, being guided between the 25 bottom of the chute 11 and a retaining plate 46 which extends downwardly from the ring connecting piece 47 formed intermediate the length of said chute 11, said retaining plate being curved forwardly at its 30 lower end to permit the outward and more horizontal movement of the covers caused by the flaring of the lower ends of the drums 21.

The covers, as they are thus directed and 40 separated between the drums 21, successively and individually engage the teeth of the ratchet disk 48 secured to a shaft 49 journaled in suitable bearings in the frame, each cover thereby rotating said shaft a predetermined amount. The teeth of the disk extend through a slot 51 in the lower part of the chute 11 and are so disposed that each cover engages one tooth, rotating the disk a given amount sufficient to disengage the 45 cover and present the succeeding tooth for actuation by the next cover. Carried on the end of the shaft 49 is a worm 52, meshing with a worm wheel 53 mounted upon a stud 54 carried by an adjustable bracket 55 secured to the side of the frame.

The counting of the ends is governed by 50 this worm wheel 53 in a manner to be now described.

A bail 56 is pivoted at 57 to the frame of 55 the machine and has a notch 58 cut in the front edge thereof. Said bail is normally held in raised position and is adapted to fall forwardly to cause said notch 58 to engage over the bars 39 after a predetermined number of ends have passed through the counter.

This is accomplished by means of an extension 59 secured to a side of said bail and having a downwardly and rearwardly extending foot portion 61 normally engaging the face of a disk 62 secured to the upper 70 side of the worm wheel 53. Said disk is formed with a radial slot 63 into which the foot portion of said extension is adapted to enter after completion of one revolution of said worm wheel. This permits the bail 56 75 to turn upon its pivots 57, causing the notch 58 to engage over the bars 39, preventing separation thereof and thus discontinuing the feeding of the covers. In starting the count of the machine, the recess 63 is adjacent the foot 61 of the extension 59 and the bail 56 must be raised by hand to disengage said foot 61, which, after the wheel 53 begins to rotate, rides upon the face of the disk 62, as previously stated. It will be manifest 80 that the magnitude of the counted stacks may be readily varied by the use of worm wheels of different diameter, this being rendered possible within a wide range by the adjustable bracket 55. When the bail 56 85 is permitted to drop down through the entry of the foot 61 into the recess 63 after a single revolution of the worm wheel 53, the stack of covers is supported upon the fingers 38 of the bars 39 and further feeding cannot 90 occur until said bail is lifted by the operator. The counted stack may then be removed and deposited in a packing case and another stack formed in similar manner. I provide means for stopping the action of the machine when the supply of covers in the chute 11 runs low, thus assuring that the supply 95 will not be exhausted during operation of the counter. This means comprises a bell crank lever 64, pivoted at 65 to a yoke 66 supported by the ring connecting piece 47, the upper arm of said bell crank being disposed in a slot 67 in a forked bar 68 having at its lower end a foot 69 formed with a notch 71, similar to the notch 58 in the bail 100 56. The lower arm of the bell crank 64 is normally disposed in the path of travel of the covers in the stack 19 and is held in raised position thereby. When, however, the stack decreases in height to a point below 105 said arm, the weight thereof causes it to drop down, permitting the bar 68 to move forwardly and causing the notched foot 69 to engage the bars 39, preventing separation thereof in the manner hereinbefore described in connection with the bail 56, 110 whereupon no covers can be fed until the stack in the chute 11 has been renewed.

It is thought that the invention and many 115 of its attendant advantages will be understood from the foregoing description, and it will be apparent that various changes may be made in the form, construction and arrangement of the parts without departing 120 from the spirit and scope of the invention, 125 130

or sacrificing all of its material advantages, the form hereinbefore described being merely a preferred embodiment thereof.

I claim:

5. 1. A machine for counting can ends, comprising parallel grooved and flared drums for grasping, separating and conveying said ends, counting mechanism, and means actuated by the covers as they are held and 10 propelled by said drums for operating said counting mechanism.

2. A machine for counting can ends, comprising positive grasping and feeding devices, counting mechanism, and means actuated by the covers as they are propelled by said feeding devices and held in position 15 for operating said counting mechanism, said feeding devices comprising rotatable grooved cylindrical drums provided with means for directing the covers therebetween 20 and lengthwise thereof during rotation.

3. A machine for counting can ends, comprising positive feeding devices, counting mechanism, and means actuated by the covers as they are propelled by said feeding devices for operating said counting mechanism, said feeding devices comprising rotatable cylindrical drums provided with means for directing the covers therebetween 30 and lengthwise thereof during rotation, said drums being flared outwardly at their lower ends for the purpose of altering the axial position of and stacking the covers as they are transferred from the line of delivery to 35 the place of deposit.

4. A machine for counting can ends, comprising a vertically disposed delivery chute, a horizontally disposed stacking chute, grooved transfer drums disposed between 40 said chutes and flared outwardly at the lower ends thereof whereby to change the axial position of the covers, and means for counting the covers transferred to said stacking chute.

45. 5. A machine for counting can ends, comprising a vertically disposed delivery chute, a horizontally disposed stacking chute, grooved transfer drums disposed between 50 said chutes and flared outwardly at the lower ends thereof whereby to change the axial position of the covers, and counting mechanism actuated by the covers as they are positively moved by said transfer drums.

6. A machine for counting can ends, com-

prising grooved elements for holding can 55 covers against sidewise pressure and feeding the covers so held in separated relationship, a ratchet wheel actuated by contact with said covers, and means for terminating the feeding of the covers after predetermined 60 rotary movement of said ratchet wheel.

7. A machine for counting can ends, comprising grooved elements for holding can 65 covers against sidewise pressure and feeding the covers so held in separated relationship, a ratchet wheel actuated by contact with said covers, and means for terminating the feeding of the covers after predetermined 70 rotary movement of said ratchet wheel, said means comprising a pivoted locking member normally held out of locking position and a releasing device automatically operable upon completion of predetermined 75 rotation of said ratchet wheel for permitting said locking member to move into locking position.

8. A machine for counting can ends, comprising a delivery chute, a stacking chute, means for transferring the can covers from 80 one said chute to the other, means for counting the covers so transferred, and means controlled by the stacked covers in the delivery chute for preventing the transfer of covers when the supply thereof runs low in 85 said delivery chute.

9. A machine for counting can ends, comprising a delivery chute, a stacking chute, means for separating individual covers from 90 a stack in said delivery chute, means for transferring the separated covers to said stacking chute, means for counting the covers so transferred, and means for locking 95 said separating means to prevent operation thereof after a stack of predetermined number has been formed in said stacking chute.

10. A machine for counting can ends, comprising a delivery chute, a stacking chute, means for separating individual covers from a stack in said delivery chute, means for transferring the separated covers to said stacking chute, means for counting the covers so transferred, and means controlled by the covers in place in the delivery 100 chute for locking said separating means to prevent operation thereof when the supply of covers runs low in said delivery chute.

JOHN RICHARD EDWARDS.
